US0D1111859S

(12) United States Design Patent (10) Patent No.: US D1,111,859 S
(45) Date of Patent: * Feb. 10, 2026

(54) WATCH

(71) Applicant: Blancpain SA, Le Brassus (CH)

(72) Inventor: Gregory Kissling, Biel/Bienne (CH)

(73) Assignee: Blancpain SA, Le Brassus (CH)

() Term: 15 Years

(21) Appl. No.: 29/951,073

(22) Filed: Jul. 8, 2024

(30) Foreign Application Priority Data

Jan. 8, 2024 (WO) WIPO142777

(51) LOC (15) Cl. 10-02
